UNITED STATES PATENT OFFICE.

JOSEPH A. KLOEB, OF PIQUA, OHIO.

FLOOR-FURNACE.

1,073,610.

Specification of Letters Patent. Patented Sept. 23, 1913.

Application filed April 9, 1912. Serial No. 689,510.

To all whom it may concern:

Be it known that I, JOSEPH A. KLOEB, a citizen of the United States, residing at Piqua, in the county of Miami and State of Ohio, have invented certain new and useful Improvements in Floor-Furnaces, of which the following is a specification.

The present invention relates in general to stoves and furnaces, and more particularly to that type of furnaces which are constructed in such a manner as to be utilized both as a hot air heater and also to heat water for a steam or hot water system.

The object of the invention is to provide an improved furnace of this character in which the heat produced by the combustion of the fuel is utilized to the fullest possible extent, which is strong and durable in its construction, and in which the various parts are compactly arranged so as to occupy a minimum amount of space.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:—

Figure 1 is a vertical sectional view through a floor furnace constructed in accordance with the invention, the said furnace being constructed to use gas as fuel. Fig. 2 is a horizontal sectional view on the line 2—2 of Fig. 1. Fig. 3 is a detail sectional view of the water head, the line of section for this view being indicated by the line 3—3 of Fig. 1. Fig. 4 is a vertical sectional view through a slightly modified form of floor furnace which is constructed to use coal as fuel, and Fig. 5 is a side elevation of a still further modification in which the heater is arranged in a casing adapted to rest upon the floor in the usual manner.

Corresponding and like parts are referred to in the following description and indicated in all the views of the drawings by the same reference characters.

In carrying out the invention, the heater or radiator proper may be utilized in any convenient or practical manner in connection with any hot water, steam or hot air system, or for other heating purposes, al-

though the preferable embodiment of the invention resides in associating the said heater or radiator with a jacket adapted to be hung or suspended below the floor of a building, whereby the entire apparatus constitutes what may properly be termed a "floor furnace."

Specifically describing the embodiment of the invention illustrated by the first three figures of the drawings, the numeral 1 designates an outer jacket or casing which is arranged in an upright position and is open at the upper and lower ends thereof. This jacket 1 is adapted to be suspended below the floor 2 of a building, and is shown as having the upper end thereof secured to a register 3 which is fitted in the floor and is flush therewith so as to form in effect a part of the floor. The lower end of the jacket 1 has a refuse catch pan 4 suspended below the same by means of the straps or hangers 5, ample space being provided between the jacket and the pan 4 to admit of a free circulation of air upwardly through the jacket.

The heater proper is mounted within the jacket 1 and is smaller than the jacket so as to provide an air space between the jacket and the heater. In the present instance the heater is arranged centrally within the jacket 1 and held rigidly in position by means of the brackets or braces 6. The heater includes an upper heating drum 7 and a lower heating drum 8 which are connected by the upright circulating and radiating tubes 9 and 10. A tubular combustion chamber 11 communicates with the bottom of the upper drum 7 at the middle portion thereof and extends downwardly entirely through the lower drum 8. A burner 12 is arranged within the combustion chamber 11 and receives suitable liquid or gaseous fuel from a fuel supply pipe 13. A valve 14 is interposed in the length of this fuel supply pipe 13 and is connected by a rod 15 to a finger piece 16 which is arranged in a convenient position above the floor of the building. Through the medium of this finger piece 16 the supply of fuel to the burner 12 can be regulated as found necessary.

A tubular water head 17 is mounted with in the upper drum 7 and the upper portion of the combustion chamber 11. The body portion of the water head fits accurately within the upper portion of the heating

drum 7, the said water head being formed with an annular pendent water leg 17^a which projects downwardly into the upper portion of the combustion chamber 11. A water supply pipe 18 leads to the lower end of the water leg 17^a while an outlet pipe 19 leads from the upper end of the water head. It will also be observed that a series of vertically arranged water pipes 20 extend centrally through the circulating and radiating tubes 9 and 10 and communicate at their upper ends with the body portion of the water head 17, the lower ends of the said water pipes 20 extending below the jacket 1 and communicating with a supply pipe 21.

A smoke pipe 22 leads laterally from one side of the upper heating drum 7 at a point below the body portion of the water head 17, the opposite side of the said body portion of the water head being formed with a substantially radial passage 23 which leads from the central opening through the tubular water head to one side of the water head and communicates through the bottom of the body portion of the water head with the upper heating drum 7. A transverse partition 24, shown more clearly in Fig. 2, extends across the interior of the upper heating drum 7 so as to subdivide the same into two chambers or compartments, the compartment A on one side thereof communicating with the circulating tubes 9 and the radial passage 23 of the water head, while the compartment B on the opposite side thereof communicates with the smoke pipe 22. The opening at the upper end of the water head 17 and at the central portion of the upper drum 7 is normally closed by a door 25, and as the products of combustion rise from the burner 12, they circulate freely around the water leg 17^a and through the same. These products of combustion enter the chamber A and then pass through the circulating tubes 9 to the lower drum 8. From this lower drum 8 the products of combustion rise through the circulating tubes 10 to the chamber B of the upper drum and pass to the chimney through the smoke pipe 2. The products of combustion thus traverse the full length of the heater three times before finally reaching the smoke pipe and the heat is in this manner utilized to the fullest possible extent. The heat radiated from the various parts of the heater serves to heat the air in the jacket 1 and this heated air rises through the register 3 and enters the room above so as to supply the same with hot air. It will also be obvious that the products of combustion act upon the tubular water head and also upon the water pipes 20 which pass centrally through the circulating tubes 9 and 10 so as to heat the water within the water head. This water may be caused to circulate through the usual radiators of a hot water system, or a smaller amount of water

may be employed and the steam thereof caused to circulate through the radiators of a steam heating system.

It will be observed that the intermediate portion of the transverse partition 24 is curved or bulged toward the smoke pipe 22 so as to cut off the upper end of the combustion chamber 11 from direct communication with the smoke pipe. This curved portion of the partition 24 may be provided with a damper 26 for the purpose of producing a direct draft when starting a fire. After the fire had been started, however, this direct draft damper would be closed and the products of combustion caused to follow the circuitous path outlined above.

A slight modification is shown in Fig. 4, in which the heater is constructed to consume coal as fuel. Referring to this figure, the numeral 1^a designates a jacket which is very similar to the jacket 1 and is secured at its upper end to a register 3^a in the floor 2^a. The upper end of this jacket may also be secured to the joist, if desired, by means of braces 27. The upper and lower drums 7 and 8 are secured within the jacket 1^a, as in the previous instance by means of the braces 6^a. These drums 7 and 8 are connected by the combustion chamber 11 and circulating tubes 9 and 10 as in the previous instance. The lower portion of the combustion chamber 11 is provided with a grate 28 for the support of the burning coal, an ash pit 29 being arranged under the grate and the usual damper 30 being arranged upon one side of the ash pit. This damper may be controlled by means of a chain 31 which passes upwardly through the floor 2^a. A water head 17^b, somewhat similar to that previously described, is arranged in the upper portion of the upper drum 7 and combustion chamber, the tubular passage through the center of the water head 17^b serving as a magazine for receiving the coal and feeding it downwardly to the zone of combustion as required. A magazine 32 is arranged over the upper drum 7 and serves to feed coal to the passage through the tubular water head. Coal may be placed in the magazine 32 either at the upper end thereof or through a lateral branch 33, the said upper end of the magazine being normally closed by a cover 34, while the lateral branch is normally closed by means of a door 35. With this construction fuel can be supplied to the furnace either from above the floor or from below the floor, as may be desired. The transverse partition 24 is arranged in the upper heating drum 7 exactly as previously described so that the products of combustion follow the same circuitous path and travel the full length of the furnace three times before finally entering the smoke pipe 22. The usual damper 36 is mounted within the smoke pipe and

may be controlled by means of a chain 37 passing upwardly through the floor 2^a. A door 38 may be provided in one side of the combustion chamber, and if desired small doors 39 may be provided in the sides of the 5 lower heating drum 8.

A still further modification is shown in Fig. 5, in which the heater or furnace proper is constructed exactly the same as is shown 10 upon Fig. 1, although instead of being mounted in a suspended jacket, it is arranged within a casing 39^a adapted to rest upon the top of a floor or other surface and be supported by the legs 40. This casing 39^a 15 would serve to radiate the heat and convey the hot air into the room, while the water in the water head would also be heated exactly as in the previous instance.

Having thus described the invention, what 20 I claim as new and desire to secure by Letters Patent, is:—

1. A furnace including upper and lower heating drums, circulating flues connecting the drums, a combustion chamber extending 25 between the drums and communicating with the upper drum, a water head mounted within the upper drum, circulation pipes leading to and from the water head, and a transverse partition dividing the upper 30 drum into two compartments both of which communicate through the circulation flues with the lower drum and one of which communicates with the smoke pipe while the other communicates with the combustion 35 chamber, the products of combustion after entering the upper heating drum passing downwardly through a portion of the circulation flues to the lower heating drum and then upwardly through the remaining circulation flues to the upper heating drum 40 before entering the smoke pipe.

2. A furnace including upper and lower heating drums, circulation flues connecting the drums, a combustion chamber extending 45 between the drums and communicating with the upper drum, a water head in the upper drum, water pipes extending through the circulation flues and communicating with the water head, a smoke pipe communicating 50 with one of the drums, and means for causing the products of combustion to circulate through the drums and the circulation flues before entering the smoke pipe.

3. A furnace including upper and lower 55 heating drums, circulation flues connecting the drums, a combustion chamber extending between the drums and communicating with the upper drum, a tubular water head arranged within the upper drum and formed 60 with a water leg extending into the combustion chamber, water pipes extending through the circulation flues and communicating with the water head, a smoke pipe leading from one of the heating drums, and 65 means for causing the products of combus-

tion to circulate through the heating drums and circulation flues before entering the smoke pipe.

4. A furnace including upper and lower 70 heating drums, circulation flues connecting the drums, a combustion chamber extending between the drums and communicating with the upper drum, a tubular water head formed with an enlarged body portion which is fitted within the upper heating 75 drum and also with a contracted tubular leg which is pendent from the body portion and projects downwardly into the combustion chamber, circulation pipes in communication with the water head, a smoke pipe leading from one of the heating drums, and 80 means for causing the products of combustion to circulate through the heating drums and circulation tubes before entering the smoke pipe.

5. A furnace including upper and lower 85 heating drums, circulation flues connecting the drums, a combustion chamber extending between the drums and communicating with the upper drum, a water head formed with 90 an enlarged body portion which is fitted within the upper drum and also with a contracted tubular water leg which is pendent from the body portion and projects downwardly into the combustion chamber, water 95 pipes passing through the circulation flues and communicating with the body portion of the water head, circulation pipes communicating with the water head, a smoke pipe leading from one of the drums, and 100 means for causing the products of combustion to circulate through the drums and the circulation flues before entering the smoke pipe.

6. A furnace including upper and lower 105 heating drums, circulation flues connecting the drums, a combustion chamber extending between the drums and communicating with the upper drum, a water head formed with 110 an enlarged body portion fitted within the upper drum and also with a contracted tubular water leg which projects downwardly into the combustion chamber, the said body portion of the water head being formed with a passage leading from the 115 opening through the tubular water leg to the interior of the drum so that the products of combustion can circulate through the interior of the water leg, a smoke pipe leading from one of the drums, and means for causing the products of combustion to circulate 120 through the drums and circulation flues before entering the smoke pipe.

7. A furnace including upper and lower 125 heating drums, circulation flues connecting the drums, a combustion chamber extending between the drums and communicating with the upper drum, a water head formed with an enlarged body portion fitted within the upper drum and also with a contracted 130

tubular water leg extending downwardly into the combustion chamber, water pipes extending through the circulation flues and communicating with the body portion of the water head, a smoke pipe communicating with the upper drum, a transverse partition subdividing the upper drum into two compartments for causing the products of combustion to circulate through the two drums and the circulation flues before entering the

smoke pipe, and a direct draft damper in the partition for producing a direct draft when necessary.

In testimony whereof I hereunto affix my signature in the presence of two witnesses. 15
